UNITED STATES PATENT OFFICE

157,277

CONTROL UNIT FOR WASHING MACHINES

Jack Morgan, Chicago, Ill., assignor to Automatic Washer Company, Newton, Iowa, a corporation of Delaware

Application May 29, 1948, Serial No. 146,691

Term of patent 7 years

(Cl. D49—1)

To all whom it may concern:

Be it known that I, Jack Morgan, a citizen of the United States, residing at Chicago, in the county of Cook and State of Illinois, have invented a new, original, and ornamental Design for a Control Unit for Washing Machines, of which the following is a specification, reference being had to the accompanying drawing, constituting a part thereof.

Fig. 1 is a top plan view of a control unit for washing machines showing my new design;

Fig. 2 is an end view thereof; and

Fig. 3 is a side elevational view thereof.

The dominant features of my design reside in those portions shown in full lines.

I claim:

The ornamental design for a control unit for washing machines, substantially as shown and described.

JACK MORGAN.
